UNITED STATES PATENT OFFICE.

MAURICE BLOCK, OF CHICAGO, ILLINOIS, ASSIGNOR TO BLOCK PORTELIER COMPANY, OF CHICAGO, ILLINOIS, A CORPORATION OF ILLINOIS.

DESIGN FOR A LIGHTING FIXTURE.

Application filed May 18, 1927. Serial No. 22,025. Term of patent $3\frac{1}{2}$ years.

To all whom it may concern:

Be it known that I, MAURICE BLOCK, a citizen of the United States, residing at Chicago, in the county of Cook and State of Illinois, have invented a new, original, and ornamental Design for a Lighting Fixture, of which the following is a specification, reference being had to the accompanying drawings, forming a part thereof, wherein:—

Fig. 1 is a view in elevation of my new and original lighting fixture with a base therefor shown in dotted outline.

Fig. 2 is a fragmentary top plan view of the arms and bowl, the balance of the ornamentation within the outline being a repetition of the fragment shown.

I claim:—

The ornamental design for a lighting fixture substantially as shown.

MAURICE BLOCK.
